(No Model.)

G. FROST.

SLEEVE SUPPORTER.

No. 313,584.

Patented Mar. 10, 1885.

UNITED STATES PATENT OFFICE.

GEORGE FROST, OF NEWTON, MASSACHUSETTS, ASSIGNOR OF TWO-THIRDS
TO GEORGE A. PHELPS AND GEORGE A. FROST, OF SAME PLACE.

SLEEVE-SUPPORTER.

SPECIFICATION forming part of Letters Patent No. 313,584, dated March 10, 1885.

Application filed January 31, 1883. (No model.)

To all whom it may concern:

Be it known that I, GEORGE FROST, of Newton, county of Middlesex, State of Massachusetts, have invented an Improvement in Shirt-Sleeve Supporters, of which the following description, in connection with the accompanying drawings, is a specification, like letters on the drawings representing like parts.

This invention has for its object the production of a simple and serviceable device for supporting shirt-sleeves.

My invention consists in a cord, one part of which is made into a loop and has a garment-clasp attached thereto, another part of the cord constituting the other end of the supporter, having attached to it a hook adapted to engage the looped part of the cord with which the clasp is attached. Stocking-supporters as commonly made have a loop of cord and a connected elastic or india-rubber web, with which is attached the hook referred to; but such web is expensive as compared with cord, and soon becomes injured if not kept in use, and fails to remain elastic. For use in shirt-sleeves the elastic web is not as good or durable as the cord, and the latter makes a stronger and more serviceable supporter.

Figure 1 represents in perspective a shirt-sleeve supporter embodying my invention, and Fig. 2 a modification thereof.

The cord *a* in Fig. 1, supposed to be endless,

has its ends *b* held together by a metal plate, *d*, connected with a hook, *e*. The cord at the other end of the supporter is made into a loop, *f*, the size of which is limited by the position of the metal clip *g*. On the loop *f* is placed the clasp *h*, of usual construction. The drawings show the supporter hooked together as it would appear if on the arm and in use.

In Fig. 2 I have shown the supporter as composed of one single strand of cord between the clip *g* and part *d e*, to hold the cord and engage the loop *f*. The cord-supporter, if laid aside for some months, will not become worthless, as in the case of supporters employing elastic web.

I claim:

As an improved article of manufacture, a garment-supporter composed of a cord bent on itself, a metal clasp to fasten one end of the cord to itself to form a loop, a hook connected with one end of the said cord and adapted to engage the said loop, and a garment-engaging clasp suspended by or connected with the looped part of the said cord, substantially as described.

In testimony whereof I have signed my name to this specification in the presence of two subscribing witnesses.

GEORGE FROST.

Witnesses:

Jos. P. LIVERMORE,
W. H. SIGSTON.
